Primary Examiner — Cathron C Brooks*Assistant Examiner* — Samantha Q Lawrence(74) *Attorney, Agent, or Firm* — Fitch, Even, Tabin & Flannery, LLP(57) **CLAIM**

I claim the ornamental design for an ear cleaner, as shown and described.

DESCRIPTION

FIG. 1 is a perspective view of an ear cleaner, showing my new design;

FIG. 2 is a top plan view thereof;

FIG. 3 is a bottom plan view thereof;

FIG. 4 is a side elevational view thereof, the opposite side elevational view being a mirror image thereof;

FIG. 5 is a rear elevational view thereof; and,

FIG. 6 is a front elevational view thereof.

The broken lines shown in FIGS. 1, 2, 3, 4, and 5 illustrate portions of the ear cleaner that form no part of the claimed design. The dot-dashed broken lines in FIGS. 1, 2, 3, and 4 represent an unclaimed boundary that forms no part of the claimed design.
